UNITED STATES PATENT OFFICE.

WILLIAM D. HICKS, OF INGLEWOOD, CALIFORNIA.

PLASTER LATH.

Application filed March 31, 1925, Serial No. 19,614.

This invention relates to lath for the reception of plaster, stucco and similar wall-forming compositions, and relates more particularly to that type formed from wire or other metal strands adapted to be affixed to a paper backing, the whole of which is to be applied to the wall for the reception of the composition.

An object of the invention is to provide a metal lath body which shall be strong, rigid and highly efficient. A further object is to provide metal lath which will present the major portion of its composition-receiving parts in spaced relation to the surface to which it is to be applied so that said lath portions will be disposed well within the composition and securely retain the latter.

Another object is to provide such a structure, wherein offset bends are provided for spacing the body of the lath from the structure to which it is applied, which structure shall be trussed to render the same rigid and prevent any tendency to sag about said bends as hinges.

A further object is to provide lath of the character stated which shall present a smooth and even outwardly disposed working surface to which the wall-forming composition is to be applied, so that the same may be readily worked with a trowel or other tool without engagement with any projections during the operation.

It is also an object of this invention to permit assembly of lath of the class stated with a flexible backing sheet in spaced relation thereto as by means of offset bends or projections to which bends or projections the sheet is secured. Said sheet preferably is water-proofed and is then coated with a layer of absorptive substance such as kieselguhr to insure a good bond with the plaster or other composition.

Briefly, the invention comprises a plurality of separate metal strands in the form of wire or the like which extend longitudinally of the resulting strip in spaced relation, zig-zag connecting strands being disposed therebetween and forming a mesh construction. At each juncture of the connecting strands with the longitudinal strands, the various strands are bound together and offset in the form of projecting bends which serve as spacers for properly positioning the lath body with respect to the structure to which the lath is to be applied. The means for bending or tying the strands together are

disposed below the surface or plane determined by the body portions of the strands so that a smooth working surface is provided. A flexible backing is secured to said spacing bends. The longitudinal strands serve to truss the meshes and make a rigid structure.

The invention resides in the combination and arrangement of parts and features of construction disclosed in certain forms in the drawings, described hereinafter and pointed out in the claims, it being understood that the invention is limited only as defined by the claims.

In the accompanying drawings wherein certain embodiments of the invention are disclosed by way of illustration,

Figure 1 is a plan view of the lath in position on the paper backing;

Figure 2 is a longitudinal section taken on the line 2-2 of Figure 1;

Figure 3 is a cross section taken on the line 3-3 of Figure 1; and

Figures 4 and 5 are diagrammatic showings indicating the relative relation of the offset bends or spacing projections of the zig-zag connection strands (Fig. 4) and longitudinal trussing strands (Fig. 5).

The metallic portion of the lath is composed of a plurality of spaced longitudinally extending trussing strands and a plurality of zig-zag connecting strands disposed between the trussing strands. The longitudinally extending strands 8, 10, 12 and 13 are shown as being connected by means of zig-zag strands 14, 15 and 16, and the bound portions of the various strands are offset to provide spacing bends of uniform extent. Thus the bends formed in the connected portions of the strands 10, 14 and 15, which bends are indicated by A and A' consist of the sections 10' of the strand 10 lying at the bottom of the bend and portions 14' and 15' of the zig-zag strands 14 and 15, respectively lying parallel with and on opposite sides of said portions 10'. The bottom portions 10', 14' and 15', respectively, are connected with the body sections 10, 14 and 15 by means of angularly disposed connection portions 110, 114 and 115.

A similar offset spacing bend in the strands 12, 15 and 16 is indicated at B. In this instance the bottoms of the bent portions are indicated at 12', 15' and 16', these portions being jointed with the upper body sections of the strands 12, 15 and 16 by

angularly disposed connecting portions 112, 115 and 116.

The portions forming each of the offset spacing bends A, A' and B, as well as the other bends not indicated by reference characters, are bound together by means of ties or clips 20 disposed about the parts 110, 112, 114, 115 and 116 at points slightly below the plane determined by the upper faces of the body sections of the strands forming the body of the lath. In this manner a smooth working surface is provided over which a trowel or other tool may be passed freely without interruption by engagement 15 with any projecting part.

It will be seen that the upper sections of the strands 8, 10, 12 and 13 serve to truss the meshes in the structure formed and obviate any tendency of the structure to sag 20 or bend about the offset spacing bends A, A' and B, thereby lending considerable rigidity to the structure.

The mesh lath construction thus produced is adapted to be mounted upon a flexible 25 backing sheet 25 of suitable building paper or pulp board and to be spaced therefrom by means of the offset spacing bends above described, staples 24 being provided for engaging over the bottom portions of the bands 30 and passing through the backing sheet 25 as best indicated in Figures 2 and 3. This sheet 25 preferably is provided with waterproof coatings 26 on both sides and with a layer of comparatively coarse material 28 35 which will be distinctly absorptive of moisture for the purpose of insuring a good bond with the plaster or other wall-forming material subsequently applied. Such a material may be kieselguhr, otherwise known 40 as diatomaceous earth. If desired, the lower side of the sheet may be provided with a similar coating 30 of such material.

By reference to Figures 4 and 5 it will be seen that the offset bends in the zig-zag 45 strands 14, 15 and 16 are double the number of those found in the longitudinally extending strands 10 and 12, thus providing a sufficiently long section of each of said 50 longitudinal strands to extend longitudinally between the ends of the meshes to truss the same for making the structure rigid and for preventing bending about the offset spacing bends.

By this structure it will be apparent that 55 the body portions of the metal lath structure provided by the upper sections of the strands will be well embedded in the plaster coat P subsequently applied thereto in building operations, as indicated at the right of 60 Figure 2. Also it will be apparent that the angularly disposed parts 110, 112, 114, 115 and 116 along with the ties 20 will serve

further to anchor the plaster coat. At the same time the granular coat of kieselguhr on the upper side of the sheet 25 will insure 65 a good bond of the plaster coat. As above indicated, working of the material into position will be facilitated by reason of the upper sides of the strands forming the body of the lath will be smooth and free from 70 projections so that the operation of applying plaster and the like may proceed rapidly.

I claim:—

1. A lath structure comprising a wire mesh formed from a plurality of separate 75 wire strands having body sections defining a smooth working plane on one side, spacing portions of said strands projecting from the other side, and means binding said spacing portions together and disposed wholly 80 below said plane.

2. A lath structure having a mesh formation comprising a plurality of wire strands certain of which extend longitudinally and others of which are disposed between the longitudinal strands in zig-zag formation and join the same, the joined portions of said strands being bound together and offset from the body of the structure to form spacing bends, the sections of the 90 longitudinal strands between said bends serving as trusses.

3. A lath structure having a mesh formation comprising a plurality of strands joined together at intervals, the joined portions being offset from the body of the structure to form spacing bends, portions of certain of said strands serving as trusses between the offsets, a backing sheet secured to said spacing bends and thereby spaced from the body 100 of the mesh structure, said sheet having absorptive granular substance thereon to provide a bond for wall-forming composition when applied to said sheet.

4. A lath structure comprising a series of 105 parallel spaced wire strands, a zig-zag wire strand arranged between adjacent parallel strands, clips binding the parallel strands and the zig-zag strands together; the connected portions of said strands being bent 110 to form spacing members at intervals throughout the length of the longitudinal strands.

5. A lath structure comprising a series of 115 parallel spaced wire strands, a zig-zag wire strand arranged between adjacent parallel strands, clips binding the parallel strands and zig-zag strands together; the connected portions of said strands being bent to form 120 spacing members at intervals throughout the length of the longitudinal strands, said binding clips being located wholly within the bent spacing members.

WILLIAM D. HICKS.
